(57) **CLAIM**

The ornamental design for an artificial fishing lure, as shown and described.

DESCRIPTION

FIG. 1 is a front, top, left side perspective view of an artificial fishing lure.

FIG. 2 is a top view of the artificial fishing lure of FIG. 1.

FIG. 3 is a bottom view of the artificial fishing lure.

FIG. 4 is a right-side view of the artificial fishing lure.

FIG. 5 is a left-side view of the artificial fishing lure.

FIG. 6 is an inferior view of the artificial fishing lure; and,

FIG. 7 is a superior view of the artificial fishing lure.

The broken lines in the drawings illustrate portions of the fishing lure forming no part of the claimed design.
